[57] CLAIM

The ornamental design for a combined tape dispensing and coating apparatus for use with dry walls, as shown.

DESCRIPTION

FIG. 1 is a perspective view of a combined tape dispensing and coating apparatus for use with dry walls, showing our new design;

FIG. 2 is an elevational view of one side, the opposite side being a mirror image thereof;

FIG. 3 is a top plan view;

FIG. 4 is a bottom plan view;

FIG. 5 is an elevational view from the right-hand end of FIG. 2; and,

FIG. 6 is an elevational view from the left-hand end of FIG. 2.
